F. E. ROBERTS.
METHOD OF MAKING BOOTS AND SHOES.
APPLICATION FILED JULY 20, 1920.

Patented June 28, 1921.

UNITED STATES PATENT OFFICE.

FRANK E. ROBERTS, OF LYNN, MASSACHUSETTS, ASSIGNOR OF ONE-FOURTH TO ALBERT N. BLAKE AND ONE-FOURTH TO FRANK C. STETSON, BOTH OF LYNN, MASSACHUSETTS, AND ONE-FOURTH TO FREDERICK W. HOWE, OF SWAMP-SCOTT, MASSACHUSETTS.

METHOD OF MAKING BOOTS AND SHOES.

1,383,237.

Specification of Letters Patent. Patented June 28, 1921.

Application filed July 20, 1920. Serial No. 397,695.

To all whom it may concern:

Be it known that I, FRANK E. ROBERTS, a citizen of the United States, residing at Lynn, in the county of Essex and State of Massachusetts, have invented certain new and useful Improvements in Methods of Making Boots and Shoes, of which the following is a specification.

My invention relates to boots and shoes and has reference particularly to the method of making boots and shoes of that class which have molded outersoles.

It has been the practice to mold the outersoles of certain kinds of boots and shoes, particularly women's boots and shoes, so as to form a sharply defined angle or corner extending across the sole at the junction of the shank with the fore-part, that is, just back of the ball, so as to give a pronounced arch to the shank which starts upwardly abruptly from the rear end of the fore-part. It also has been the practice to mold the shank of the outersole so that it was more or less V-shaped in cross-section with a sharply defined median ridge or corner upon the exterior thereof extending from the first mentioned transverse corner or angle at the rear of the fore-part to the breast of the heel. This peculiar molding of the outersole, sometimes referred to as the "Cottage Roof" shape, has the advantage of improving the appearance of the boot or shoe and also of stiffening the shank.

In my co-pending application, filed August 20, 1919, Serial Number 318,771, I have illustrated and described a shoe whose outersole is molded to the "Cottage Roof" shape after the parts of the shoe have been assembled upon the last, and my present invention has for its object to provide a simple, expeditious, economical and efficient method of making shoes of this kind.

In making a boot or shoe constructed as described in said application, the upper and innersole are first assembled upon a last and a bolstering member is placed in position upon the innersole at the place where the sharply defined bend or corner is desired in the outersole. The outersole is then secured in place and beaten down so as to utilize the bolstering member to give the desired shape to said outersole.

In making a boot or shoe in accordance

with my present invention the parts may be assembled upon the last and secured together as described in said application, but the beating down of the outersole is effected by blows or pressure delivered onto said outersole by any suitable instrument, preferably a rotating wheel, in the peculiar fashion hereinafter described which stretches or crowds the material of the outersole toward the apex of the corner or bend with the result that a very sharply defined and accurately formed ridge or corner is produced.

In the accompanying drawings;

Figure 1 is a perspective view of the bottom portion of a shoe having a "Cottage Roof" sole, said view including also a portion of a beating down wheel which is shown by dotted lines.

Fig. 2 is a perspective view of the bolstering member hereinafter referred to.

Fig. 3 is a perspective view of a portion of the beating down wheel hereinafter referred to.

Fig. 4 is a sectional detail of the wheel shown in Fig. 3.

In constructing the shoe of Fig. 1 the upper and inner sole are lasted and sewed together as usual after which the usual filler is spread over the fore-part of the innersole between the edges of the upper. I next place upon the innersole, immediately at the rear of the filler, a bolster member 9, Fig. 2, said bolster comprising a strip 14 extending more or less obliquely across the sole at the rear of the fore-part thereof and a stem 15 extending lengthwise of the shank 7 at the middle thereof. An unmolded outersole is then placed in position and sewed to the upper and welt in the usual fashion after which the outersole is trimmed.

The rear end of the forepart and the shank 7 of the outer sole are then beaten down to shape them to the last and also bend or fold the sole sharply around the bolster member 9, the strip 14 of the latter producing a sharply defined bend or corner 6 upon the exterior of the sole extending somewhat diagonally across the latter, and the stem 15 of said bolster member giving to the shank a V-shape in cross-section with a sharply defined ridge 8 at the middle of the exterior of the shank which extends from the bend or corner 6 to the breast of the heel.

In proceeding according to my present invention the beating down of the outersole is effected by glancing or rubbing blows delivered onto the sole by any suitable instrument. This step of the process may be carried out as follows:—

After the upper, inner sole, bolster members and outer sole have been assembled upon the last, and the inner and outer soles have been sewed to the upper, the shoe, still upon the last is manually presented, as shown in Fig. 1, to a rapidly rotating wheel 12 formed with a roughened or corrugated periphery 13 and is shifted about relatively thereto so that the elevations of said periphery deliver a succession of glancing or wiping blows upon the tread side of the outersole as indicated by the arrows. The wheel 12 is caused to traverse both sides of corners 6 and ridge 8, the workman grasping the opposite ends of the shoe with his hands and pressing said shoe against wheel 12 with his hip. The shoe is presented to wheel 12 so that each peripheral elevation of the wheel strikes the outersole at one side of the line of the corner 6, or ridge 8 that is being formed and wipes or slides on the sole toward said line. This method of procedure beats the outersole down against the last and bolstering means and also crowds the material of the outersole more or less toward the corner 6 and ridge 8 with the result that the latter are very accurately produced and sharply defined. Moreover, this method is expeditious and economical, as by it a skilled workman can completely mold the sole of a shoe of this particular kind in a very few seconds.

What I claim is:

40. 1. The method of making boots and shoes of the class described which consists in first assembling the upper and inner sole upon a last; then placing a bolstering member in position upon the innersole; then securing the outersole in place, and lastly beating down the outersole so as to shape the latter to the last and bolstering member by crowding the material of the outersole toward said bolstering member and the last simultaneously.

2. The method of making boots and shoes of the class described which consists in first assembling the upper and innersole upon a last; then placing a bolstering member in position upon the innersole; then securing the outersole in place, and lastly beating down the outersole by crowding the material of the outersole toward said bolstering member and last simultaneously. 55

3. The method of making boots and shoes 60 of the class described which consists in first assembling the upper, innersole and outersole upon a last with a bolstering member in place between the inner and outersoles and thereafter beating down the outersole 65 by crowding the material of the outersole toward said bolstering member and last simultaneously.

4. The method of shaping the outersoles of boots and shoes which consists in beating 70 down the outersole while the boot or shoe is mounted upon a last with corner-forming bolstering means supporting said outersole at the place where a corner is to be formed, said beating down being effected by wiping 75 blows directed toward said bolstering means from opposite sides of the latter.

5. The method of making boots and shoes 80 of the class described which consists in first assembling the upper, inner sole and outer sole upon a last with a bolstering member in place between the inner and outer soles, and thereafter beating down the outersole by wiping blows which are directed to strike 85 against the outer sole at one side of the bolstering member and toward said member.

6. The method of making boots and shoes 90 of the class described which consists in first assembling the upper, inner sole and outer sole upon a last with a bolstering member in place between the inner and outer soles, and thereafter beating down the outer sole at each side of said member by wiping blows 95 which are directed toward the latter.

In testimony whereof I have affixed my signature.

FRANK E. ROBERTS.
